US00D596373S

(12) **United States Design Patent**
Kang et al.

(10) **Patent No.:** US D596,373 S
(45) **Date of Patent:** ** Jul. 14, 2009

(54) **AUTOMATED TELLER MACHINE**

(75) Inventors: **Dong Gu Kang**, Gyeonggi-do (KR);
Jong Ok Lee, Gyeonggi-do (KR)

(73) Assignee: **Nautilus Hyosung Inc.**, Seoul (KR)

(**) Term: **14 Years**

(21) Appl. No.: **29/299,631**

(22) Filed: **Dec. 31, 2007**

(30) **Foreign Application Priority Data**

Jul. 6, 2007 (KR) 30-2007-0029337

(51) **LOC (9) Cl.** 20-01

(52) **U.S. Cl.** D99/28

(57) **CLAIM**

The ornamental design for an automated teller machine, as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The structural elements shown in broken lines form no part of the claimed design.

1 Claim, 5 Drawing Sheets

FIG. 1

FIG. 2

FIG. 3

FIG. 5

FIG. 6**FIG. 7**
